UNITED STATES PATENT OFFICE.

MICHAEL J. MILMOE, OF CHICAGO, ILLINOIS, ASSIGNOR TO F. B. REDINGTON COMPANY, OF CHICAGO, ILLINOIS, A CORPORATION OF ILLINOIS.

COATING MECHANISM.

1,315,740.

Specification of Letters Patent.

Patented Sept. 9, 1919.

Original application filed January 18, 1915, Serial No. 2,887. Divided and this application filed October 25, 1916. Serial No. 127,617.

To all whom it may concern:

Be it known that I, MICHAEL J. MILMOE, a citizen of the United States, residing at Chicago, in the county of Cook and State of Illinois, have invented certain new and useful Improvements in Coating Mechanism, of which the following is a specification.

This application is a division of my co-pending application for patent on automatic labeling machines, Serial No. 2,887, filed January 18, 1915.

This invention relates to mechanism for applying a coating to sheets of material, such as paper, and it is illustrated in connection with the labeling machine described and claimed in the application referred to above.

The object of the invention is to provide a device of the character named which shall be of improved construction and operation. The invention is exemplified in the combination and arrangement of parts shown in the accompanying drawings and described in the following specification, and it is more particularly pointed out in the appended 25 claims. In the drawings—

Figure 1 is a fragmentary side elevation of a portion of an automatic labeling machine to which the present invention is applied.

Fig. 2 is a top plan view of a portion of the machine shown in Fig. 1; and,

Figs. 3 and 4 are vertical sectional views taken on planes at right angles to one another of the suction-head forming a part of this invention.

The labeling machine illustrated comprises a magazine 1 for holding a stack of thin sheets of material 2, which may be paper labels to be applied to various articles.

An article to be so labeled is represented at 3, resting on a supporting device 4. The labels are extracted, one at a time, from the magazine 1 by a label-handling suction-head 5, illustrated in detail in Figs. 3 and 4.

As illustrated, the invention is employed for applying adhesives to the labels 2, but it should be understood that it may be used for applying other substances to surfaces of various articles to be coated.

A receptacle 6 is provided for holding the coating material, and a roller 7 is journaled to rotate partially within and partially without the receptacle 6. The roller may be rotated by any suitable means, there being a

rack 8 shown in the drawings for this purpose. The rack 8 drives a pinion 9, connected with a gear 10, which in turn meshes with a pinion 11, secured to the end of the roller 7. The rack 8 is reciprocated by any suitable mechanism, not shown, and the gears 9 and 10 may be provided with ratchet mechanism, if desired, for the purpose of driving the roller 7 always in one direction. A scraper 12 is positioned adjacent the portion of the roller 7 which projects above the receptacle 6 for the purpose of removing excess coating material from the roller. A series of curved fingers 13 are secured adjacent the roller 7, and are arranged with pointed ends bearing against the surface of the roller for the purpose of stripping sheets of material being coated from the surface of the roller.

The suction-head 5 is provided with a pair of screw-threaded openings 15 and 16 at its upper end, which openings are connected respectively with pipes 17 and 18, and these pipes are in turn respectively connected with suction and compression mechanism, not shown in the drawings. The pipes 17 and 18 are carried on an arm 19, pivotally secured to an upright standard 20. The arm 19 is provided with a pair of sleeves 21 and 22, through which the pipes 17 and 18 are free to slide. A collar 23 is secured to the pipes 17 and 18, and is provided with a laterally projecting stud 24, which rests upon a cam surface 25 carried at the end of an arm 26. The arm 26 is pivotally supported at 27 on the standard 20, and a link 28 is pivoted at 29 to the end of the arm. Properly timed longitudinal reciprocation is imparted to the link 28 by cam mechanisms not shown in the drawings. A link 30 is pivotally connected to the lower end of the arm 19 adjacent the sleeve 22, and the opposite end of the link 30 is pivotally connected at 31 to the upper end of a lever 32, which reciprocates about a pivotal support 33. The lever 32 is reciprocated by cam mechanism in properly timed relation with the operation of the other parts of the machine. By the combination of the vertical movement imparted to the head 5 by the arm 26, and of the horizontal movement imparted to the link 30, any desired motion may be given to the head for manipulating the sheets carried thereby. As shown in Figs. 3 and 4, the suction-

2

head consists of a hollow casting 35, which is extended laterally at its lower end to form a wide bell or mouth portion 36. A thin plate 37, preferably of metal, covers the 5 opening of the mouth portion 36, and is in turn covered on its lower surface by a comparatively thick sheet 38 of resilient frictional material, such as rubber. Since as is well known, such material does not take a 10 polish, it will retain its yielding frictional property during use. The plate 37 and the coating 38 are provided with a plurality of perforations 39 extending into the interior of the suction-head and the two plates are 15 removably secured to the suction head by screws as shown in the drawing so that plates with rubber coverings of different sizes and shapes, to conform to the different sized and shaped labels, may be interchanged. 20 ably secured to the head. A number of the perforations 39 are provided with connecting grooves 40 to assist in the operation of extracting the sheets from the magazine 1, as explained in my co-pending application 25 referred to above. A cone valve 41 is located in the upper portion of the suction-head for the purpose of connecting the interior of the head selectively with the pipes 17 and 18. The valve is held in place by a spring 42, 30 and is operated by a crank 43, which carries a cam roller 44, and which is normally held in position to connect the interior of the suction-head with the suction pipe 17 by a spring 45. Below the valve 41, the suction 35 head carries a laterally projecting hollow cylinder 46, which communicates with the interior of the suction-head. A piston 47 is fitted within the cylinder 46 forming an air-tight sliding connection therewith. A coil 40 spring 48 normally presses the piston 47 outwardly in the cylinder 46. The piston 47 carries a short rod 48, which is provided with a cam roller 49 at its outer end. The rod 48 is guided by a cover plate 50 secured 45 to the outer end of the cylinder 46, but arranged to permit passage of air between the interior of the cylinder outside of the piston 47 and the external atmosphere. A plug 51 is threaded into the interior of the suction 50 head to intercept any liquid, such as oil, that may drain downwardly in the head. Passages 52 provided with ball valves 53 are arranged to drain the oil from the interior of the suction-head to wells or reservoirs 54 55 provided in the casting 35. These wells may be filled with waste, or similar material, for absorbing the oil. A groove or trench 55 extends around the suction-head to intercept oil that may drain down the exterior of the 60 casting, and to direct the oil thus intercepted to the wells 54. A tripping member or cam track 56 is supported by the upright 20, and extends into a position to coöperate with the cam roller 44 when the suction-head 5 is lowered into position upon the article 3 to 65 be labeled. The tripping member is arranged so that when the suction-head is in position upon the article 3, the interior of the head will be connected by the valve 41 with the compression pipe 18, so that a label 70 carried by the suction-head will be discharged onto the article to be labeled. A second cam track 57 is supported on a bracket 58 in a position above the coating roller 7. As will be seen from Fig. 2, the 75 track 57 is so located that the cam roller 49 will be directly above the track when the roll is held in its outer position by the spring 48. When the spring 48 is compressed, the roll 49 will be sufficiently retracted to permit 80 descent of the suction-head 5 without the roll coming into contact with the track 57. The operation of the device is as follows:—

The magazine 1 is supplied with sheets 2 to be coated, and the cam mechanism is set 85 into operation to move the suction-head 5. The head moves first to the magazine where it lifts by suction the uppermost one of the sheets 2 from the stack. The head is then carried upwardly and forwardly, the valve 90 41 being held by the spring 45 in position to maintain connection between the head and the suction pipe 18. The head is carried forward to a position beyond the coating roller 7, and is then moved downwardly 95 to a position on a level with or slightly below the surface of the roller 7. The head is then drawn backwardly by the link 30 to move the sheet of material over the roller 7 in contact therewith, and thus apply the 100 coating to the entire under surface of the sheet. Any tendency of the sheet to adhere to the roller is overcome by the fingers 13 which bear against the surface of the roller and prevent the sheet from adhering thereto. 105 When the head has reached a position above the article 3, it is then lowered and the sheet discharged onto the article to be labeled, after which the head returns to the magazine for a second sheet. 110

During the period of the operation in which a sheet is carried by the suction-head, the interior of the suction-head will be shut off from the outer atmosphere by the sheet which covers the perforations 39. As a result a 115 partial vacuum will be formed within the head by the suction mechanism, and while this vacuum is maintained, the pressure of the atmosphere on the outer surface of the piston 46 will compress the spring 48 and 120 hold the cam roller 49 in its retracted position. Because of this fact, the head is permitted to move downwardly a sufficient amount to bring the sheet into contact with the coating roller 7. If it should happen at 125 any time that the device fails to extract a sheet from the magazine, or if the sheet lifted is not properly placed upon the suction-head, the openings 39 will not be closed, and hence the interior of the suction-head will 130

have connection with the outer atmosphere. Under this condition there will be no vacuum within the head, and hence the spring 48 will hold the roller 49 in its outer position. When under these conditions the head 5 is lowered over the coating roller 7, the cam roller 49 will strike the upper surface of the track 57 and prevent the head from contacting with the surface of the roller. 10 In this way the lifting surface of the suction-head is prevented from being smeared with the coating material when it is not protected by a sheet to be coated. The coating operation is greatly assisted by the nature of 15 the coating 38 on the holding surface of the suction-head. Since this coating is resilient, it holds every portion of the sheet in contact with the surface of the roller, so that the entire surface of the sheet is uniformly coated. 20 The frictional nature of the holding surface of the coating 38 is also important, since it prevents any slipping of the paper on the suction-head as the sheet is moved over the coating roller. This is important where substances, such as mucilage are used for coating 25 the sheet, since the sticky character of the mucilage tends to cause the sheet to adhere to the roller and thus slide the sheet on the suction-head as the head moves forwardly. 30 Connection between the coating 38 and the upper surface of the sheet prevents any such sliding action.

I claim:—

1. In a coating machine, a holder having 35 a yielding frictional surface arranged to contact with an article to be coated, means for exhausting air from between said surface and an article held thereagainst to cause atmospheric pressure to force said article 40 against said surface, a device for applying coating material, and means for moving said holder and said applying device relative to one another while one side of the article on said holder contacts with said applying device and the other side of said article is held 45 against said frictional surface and is prevented thereby from movement over the surface of said holder.

2. In a coating machine, a device having 50 a frictional surface for holding an article to be coated, said surface being formed by a substantially continuous covering of yielding material capable of clinging to a surface along which it is moved, means for exhausting 55 air from between said surface and an article held thereagainst to cause atmospheric pressure to force said article against said surface, a device for applying coating material, and means for moving said devices 60 relative to one another with an article to be coated in position therebetween and held in place on said holding device during said relative movement by atmospheric pressure and the clinging action of said cover.

3. In a coating machine, a holder having

its holding surface substantially covered with yielding frictional material having perforations therethrough, means for exhausting air from said surface through said perforations to cause an article to adhere to 70 said surface under atmospheric pressure, a device for applying coating material, and means for moving said holder and applying device relative to one another in the direction of the plane of said holding surface 75 while a sheet of material to be coated is held between said holder and said applying device, said frictional surface being formed by a substantial continuous covering of rubber having perforations therethrough. 80

4. In combination, a sheet-carrier, a glue roll, having a stationary axis, the surface of which roll is arranged to be brought into contact with a sheet on said carrier by movement of said carrier, means for rotating said glue roll, means for regulating the amount of adhesive material on the surface of said roll, and means for automatically modifying the movement of said carrier when there is no sheet on said carrier. 90

5. In a coating machine, a sheet-carrier, suction mechanism for causing sheets to be held by said carrier, a roll for applying coating material, and a frictional surface on said carrier for preventing slipping of 95 a sheet carried thereby, said frictional surface being formed by a substantially continuous covering of rubber having perforations therethrough communicating with said suction mechanism. 100

6. In a coating device, a coating roller, a sheet-carrier, suction mechanism for causing a sheet to be held on said carrier, means for passing said roller over a sheet on said carrier, and means for preventing slipping 105 of said sheet on said carrier comprising a perforated rubber covering for the sheet engaging surface of said carrier, the perforations in said carrier being arranged to communicate with said suction mechanism. 110

7. In a coating machine, a suction device for handling articles, means for supplying material for coating said articles, mechanism for moving said device relative to said supplying means, a stop carried by said suction device controlled by the degree of vacuum in said suction device, and means arranged to coöperate with said stop to control the movement of said suction device while said device continues to move. 115

8. In a coating machine, a lifter for articles to be carried, means for supplying material for coating said articles, mechanism for moving said lifter relative to said supplying means, a stop carried by said lifter, 120 means for coöoperating with said stop to guide the movement of said lifter, and means for controlling the position of said stop depending upon the operation of said lifter. 125

9. In a coating machine, a lifter for articles to be coated, means for supplying material for coating an article carried by said lifter, mechanism for moving said lifter 5 relative to said supplying means, a stop carried by said lifter, a guide arranged to cooperate with said stop to control the movement of said lifter, means for holding said stop in one position when an article 10 is carried by said lifter, and means for holding said stop in another position when no article is carried by said lifter. 10. In a coating machine, a suction-head for handling articles to be coated, means 15 for supplying material for coating articles carried by said suction head, mechanism for moving said suction head relative to said supplying means, and a plunger carried by said suction-head adapted to be forced inwardly by atmospheric pressure against the action of a resilient member and a horizontally movable guide stop for said suction-head carried by said plunger. 11. In a coating machine, a suction-head 25 for handling articles to be coated, means for supplying material for coating said articles, mechanism for moving said suction-head relative to said material supplying means, a plunger on said suction head 30 adapted to be forced inwardly by atmospheric pressure when an article is carried by said suction-head, and resilient means for forcing said plunger outwardly when no article is carried by said suction-head, 35 and a horizontally movable guide stop for said suction-head carried by said plunger. 12. In combination, a suction carrier for sheets to be coated, a roller having a fixed axis of rotation for applying adhesive to a 40 sheet on said carrier, ratchet mechanism for driving said roller and arranged to permit movement of said roller in one direction at a greater rate of speed than that imparted by said ratchet mechanism, means for moving said carrier along a path to bring a 45 sheet thereon into engagement with said roller; and a stop on said carrier controlled by the degree of vacuum therein for modifying the movement of said carrier so that 50 said carrier will not engage said roller when no sheet is carried thereby. 13. In a coating machine, a device for applying coating material, a suction-carrier, a cam track, a stop on said suction-carrier, 55 and means controlled by the degree of vacuum in said suction-carrier for moving said stop into and out of position to contact with said cam track. 14. In a coating machine, a source for 60 supplying articles to be coated, mechanism for applying coating material, a vacuum-carrier, a cam track mounted on said applying mechanism, a stop mounted on said vacuum-carrier, and means for moving said 65 stop into position to contact with said cam track when said vacuum-carrier fails to lift an article from said article-supplying source. 15. In a coating machine, a coating roller, means having a substantially continuous 70 yielding frictional surface for feeding sheets to be coated over said roller and for pressing said sheets thereagainst, and means for automatically preventing such pressure in the absence of a sheet to be coated. 75 16. In combination, a coating roller, means having a substantially continuous yielding friction surface for pressing a sheet of material against said roller and for moving said sheet in contact therewith to bring the 80 entire surface of one side thereof against said roller, and mechanism for holding said pressing means away from said roller during an operation in which no sheet is interposed between said roller and said pressing 85 means. 17. In a coating machine, a roller, means for periodically passing said roller for moving a sheet of material thereover in contact therewith, and means for driving said roller 90 in the direction of movement of said sheet, said driving means being arranged to permit movement of said roller in said direction independent of said driving means. 18. In a coating machine, a roller, cam actuated means arranged to periodically pass said roller and press a sheet against said roller and move it thereon, and an intermittent one-way drive for said roller. 95 19. In a coating machine, a roller, irregularly moving means arranged to periodically pass said roller and press the surface of material to be coated over said roller in contact therewith, and ratchet mechanism arranged to drive said roller in the direction of movement of said surface and to permit movement of said roller in said direction independent of said mechanism. 100 20. In combination, a coating roll, a suction carrier for moving sheets of material 110 in contact with said roll, said carrier having a surface for holding said sheets which has greater frictional resistance to the movement of a sheet thereover than that offered by the coating roll with the coating 115 material thereon. 21. In combination, a coating roll, and a suction carrier for moving sheets of material in contact with said roll, said carrier having a rubber covered surface for engaging said sheets. 120 22. In combination, a coating roll, and a suction carrier for moving sheets of material in contact with said roll, said carrier having the surface which engages said 125 sheets covered with a frictional material which will not take a polish. 23. In combination, a coating roll, and a suction carrier for moving sheets of material in contact with said roll, said carrier 130

having a removable plate of frictional material secured thereto for engaging said sheets.

24. In combination, a coating roll, and
5 a suction carrier for moving sheets of material in contact with said roll, said carrier having a sheet engaging member made of soft rubber removably secured thereto.

In testimony whereof I have signed my name to this specification on this 20th day 10 of October, A. D. 1916.

MICHAEL J. MILMOE.
